COMBINED AUTOMATIC PHONOGRAPH REMOTE CONTROL UNIT AND EXTENSION LOUDSPEAKER OR SIMILAR ARTICLE

Christopher John Sheils, 216 Guildwood Parkway,
Scarborough, Ontario, Canada

Filed Oct. 6, 1965, Ser. No. 87,343

Term of patent 3½ years

(Cl. D56—4)

FIG. 1

FIG. 2

FIG. 3

FIG. 4

FIG. 1 is a left side, top and front perspective view of a combined automatic phonograph remote control unit and extension loudspeaker or similar article, showing my new design;

FIG. 2 is a top plan view, to a reduced scale;

FIG. 3 is a rear elevational view, to a reduced scale, and

FIG. 4 is a left side elevational view, to a reduced scale, the right side being substantially a mirror image thereof.

Portions of the drawing figures are diagonally lined to indicate transparency.

I claim:

The ornamental design for a combined automatic phonograph remote control unit and extension loudspeaker or similar article, as shown and described.
